[57] CLAIM

The ornamental design for a cookware handle, as shown and described.

DESCRIPTION

FIG. 1 is a side, top perspective view of a cookware handle showing our new design;

FIG. 2 is a left side elevation view thereof;

FIG. 3 is a right side elevation view thereof;

FIG. 4 is a top plan view thereof;

FIG. 5 is a top plan view of a second embodiment of FIGS. 1-2 and 6-8, the only difference being the deletion of the hanger hole;

FIG. 6 is a bottom plan view of FIG. 1;

FIG. 7 is a front elevation view of FIG. 1; and,

FIG. 8 is a rear elevation of FIG. 1.

The broken line showings in FIGS. 1-8 are for illustrative purposes only and form no part of the claimed design.
